UNITED STATES PATENT OFFICE.

JOHN J. DIVEKEY, OF AURORA, ILLINOIS.

DESIGN FOR A BATH-TUB OR SIMILAR FITTING.

45,861.

Specification for Design.

Patented June 2, 1914.

Application filed January 26, 1914. Serial No. 814,597. Term of patent 7 years.

To all whom it may concern:

Be it known that I, JOHN J. DIVEKEY, a citizen of the United States, residing at Aurora, in the county of Kane and State of Illinois, have invented a new, original, and ornamental Design for a Bath-Tub or Similar Fitting, of which the following is a specification, reference being had to the accompanying drawing, forming part thereof.

Figure 1 is a front elevation of a bath tub fitting showing my new design; Fig. 2 is a rear elevation of the structure shown in Fig. 1; and Fig. 3 is a side elevation of the same.

My ornamental design for bath-tub, wash-bowl and similar fitting comprises a hollow coupling or union made from an integral casting that is provided at each end with a frustum-pyramidal embossment which is raised above the plane of the outer surface of the casting. These embossments have hollow central bores that are in axial alignment with openings formed in the rear wall of said casting and the side walls of said embossments are curved gracefully in an ogee curve that merges into the rounded

outer corners thereof. The body of the casting surrounding each of the embossments is concentric thereto and at points nearest the opposite embossment the edge of said casting sweeps in a concave curve toward and merges into the opposite concentric edge. At the center of length of the casting is a cylindrical vertically disposed stub the lower edge of which depends below the same a distance corresponding to one-half the width of the body portion. The axis of this stub is at a right-angle to the axis of the bore of said embossments and its lower corners are rounded while its upper end is semi-spherical and merges into the outer surface of the casting. Extending around the rear surface casting is a shallow rib that is made integral therewith and is concentric and parallel with the curves forming the edges of said rear portion.

The ornamental design for a bath-tub or similar fitting, as shown and described.

JOHN J. DIVEKEY.
